WRINGER

Carl Moon, Detroit, Mich.

Application August 21, 1953, Serial No. 375,756

2 Claims. (Cl. 68—263)

This invention is intended to improve wringers of the type in which the roll pressure is released by the instinctive reaction of the user in attempting to escape from the rolls by positively blocking actuation of the safety release while the roll pressure is being reset. This eliminates the tendency for the operator to defeat the resetting of the roll pressure by inadvertent actuation of the safety release. Because a substantial force is required to reset the roll pressure, while only a very small force is required to actuate the safety release, it has been found that unless a great deal of care is taken, the safety release will be actuated to release the roll pressure at the end of the resetting operation.

In the accompanying drawings, Fig. 1 is a side view partly broken away of a wringer; Fig. 2 is an end view of the manual release for the roll pressure; Fig. 3 is a top plan view showing the safety release latch bar in the latched position; Fig. 4 is a view similar to Fig. 3 showing the safety release latch bar in the released position; Fig. 5 is a section on line 5—5 of Fig. 1 with the latch release bar in the latched position; Fig. 6 is a view similar to Fig. 5 with the latch release bar in the released position; Fig. 7 is a perspective of the latch member for holding the latch release bar in the latched position; and Fig. 8 is a section on line 8—8 of Fig. 4.

The invention is shown applied to a wringer of the construction disclosed in Patent No. 2,595,149, Kauffman. As there disclosed, there is a wringer head 1 for mounting on a wringer post 2, which is yieldably indexed in the desired wringing position by a cam-faced detent 3 engaging the selected opening 4 in a collar 5 on the wringer post and there is a positive index pin 6 which is moved through one of the holes 4 in the driving position to positively index the wringer. The yielding index locates the wringer in the desired index position, but does not restrain the wringer from movement out of the index position and by itself is not safe for actual wringing. The positive index pin 6 provides the necessary restraint so as to make the wringing safe. The positive index pin is biased out of the index position by a spring 7 and is cammed downward into the index locking position whenever the gearing is moved to the driving position by the control lever 8. While the mechanism so far described is desirable, simpler forms of drive gearing and indexing may be used.

The wringer has rolls 9 and 10, which are carried in a frame comprising a lower frame 11 and a top frame 12 and which are urged together by the usual pressure mechanism (not shown). The top frame 12 is pivoted at 13 on a bracket 14 fixed to the bottom frame 11 and pivoted on the wringer head 1 on pivot screws 15 and 16. The pivot screws 15 and 16 are arranged directly above a flexible coupling 17, which connects the driving mechanism contained within the wringer head 1 with the shaft 18 of the lower roll 10. At the outer end, the top bar 12 is connected to the bottom frame by a toggle comprising an inner link 19 and an outer link 20, which are

2

pivoted together at 21. The inner link 19 is pivoted on the bottom frame at 22 and the outer link 20 is pivoted on the top frame at 23. The pivot points 21, 22, and 23 are so arranged that when the toggle links are in the set or pressure applying position, the pivot point 21 is short of a center line connecting the pivot points 22 and 23, thereby making the toggle links of the unstable type where a latching force is required to hold the toggle links 19 and 20 in the set or pressure applying position. If the pivot point 21 is almost in line with the pivot points 22 and 23, the latching force required to hold the toggle links in the set position can be very small. However, with this arrangement, due to manufacturing variations, the pivot point 21 will occasionally be slightly beyond the center line of the pivot points 22 and 23, thereby making the toggle stable. Accordingly, even if the toggle is of the unstable type, it is desirable that the latching arrangement for holding the toggle in the set position be able to release the toggle even though the pivot points of the toggle are in an over-center or stable position. The toggle 19, 20 is held in the set or pressure position by a latch release bar 24 beneath the bottom frame 11 and urged upward and to the right, as viewed in Fig. 1, by tension springs 25 and 26. At the left-hand end of the latch release bar is a stabbing 27, which engages a catch 28 fixed to the wringer head 1 and holds the latch release bar 24 in the left-hand position. At the right-hand end of the latch release bar is a tongue 29, which extends through an opening 30 in the lower end of the toggle link 21 and latches or holds the toggle in the set or pressure applying position. In this position, the lower end of the toggle link 20 butts against a tab 31 on the latch release bar, which causes the latch release bar to be moved to the left, as viewed in Fig. 1, as the toggle link comes down to the set position and the tongue 29 enters the opening 30. From one aspect, the tongue 29 and the opening 30 constitute a latch holding the toggle in set position. The stabbing 27 and the catch 28 constitute a detent, which hold the latch release bar in the latching position. It is obvious that when the left-hand end of the latch release bar 24 is depressed so that the stabbing comes below the catch 28, the springs 25 and 26 will urge the latch release bar to the right and will thereby effect a release of the toggle 19, 20. If the pivot point 21 is in an over-center or stable position, the shoulder 31 on the latch release bar will push the toggle link 20 past dead center into an unstable position. On the other hand, if the pivot point 21 is short of dead center so that the toggle 19, 20 is unstable in the pressure or set position, then the roll pressure acting on the toggle will cause the toggle to release. An inclined surface 32 on the latch release bar 24 depresses the latch release bar and moves the tongue 29 out of the opening 30 so that the latch release bar does not interfere with the opening of the toggle.

In this wringer, there are two expedients provided for releasing the toggle 19, 20 and thereby releasing the roll pressure, a manual release and an instinctive release. The manual release illustrated in Fig. 2 comprises pivoted release bars 33 on opposite sides of the wringer rolls, each of which is fixed to a bell crank lever 34 pivoted at 35 on the lower frame member 11. The bell crank levers 34 are connected by a slotted link 36 receiving pins 37 in the respective bell crank levers. A tension spring 38 between a slide 39 and one of the bell crank levers 34 urges the slide upward against the adjacent ends 40 of the bell crank levers, thereby holding the release bars in the position illustrated. With this arrangement, a push or pull on either of the release bars 33 causes one of the bell crank levers 34 to move in a direction to depress the slide 39 against the tension of the spring 38. The lower end of the slide 39 has tabs 42 which engage a

3

pair of upstanding projections 41 on the latch release bar 24 and depresses the latch release bar until the stabbing or detent 27 is below the catch 28. As soon as this point is reached, the springs 25 and 26 move the latch release bar to the right, as viewed in Fig. 1, and the toggle 19, 20 is released, as explained above.

The operation of the instinctive release depends upon a pivotal movement of the wringer frame about the screws 15 and 16 swinging the detent 27 to one side of the catch 28 and thereby permitting the springs 25 and 26 to move the latch release lever 24 to the right. Since the catch 28 is carried on the wringer head and the latch releasing lever 24 is carried on the wringer frame, it is evident from Fig. 3 that a slight pivoting movement of the frame relative to the wringer head will move the detent 27 to one side of the catch 28 and thereby effect the pressure release. The releasing action of the toggle 19, 20 is the same, whether effected by the manual release bars 33, or by the instinctive pivoting of the wringer frame relative to the wringer head.

When the roll pressure is released by the opening of the toggle 19, 20, the latch release bar 24 moves to the right, as viewed in Fig. 1, and comes to the position shown in Figs. 4 and 6 where projections 41 on the latch bar 24 move into the plane of an opening 43 in the bottom frame member and straddle depending tabs 44 on the catch 28. As is apparent from Figs. 4 and 6, the projections 41 on the latch release bar 24 cooperate with the tabs 44 on the catch 28 and the sides of the opening 43 to make an essentially rigid connection between the wringer frame and the wringer head preventing pivotal movement of the frame relative to the head. From one aspect, the projections 41 block the pivotal movement of the frame relative to the head, which is utilized to actuate the instinctive safety release. In order to position the latch release bar 24 in the Fig. 4 and 6 position, the depending tabs 44 on the catch 28 have parts 45, which cooperate with a shoulder 46 on the latch release bar 24 and limit the movement so that in the released position the projections 41 are in the plane of the opening 43 and are positioned to block the pivotal movement of the wringer frame relative to the wringer head. It is not essential that pivotal movement between the wringer frame and head be completely blocked in the roll pressure released position of the latch release bar 24. It is sufficient that while the roll pressure is released the pivotal movement between the wringer frame and head be sufficiently restricted that the catch 27 on the latch release bar 24 will always be in line with part of the latch member 28 on the wringer frame. Since the instinctive release of the pressure between the rolls can only take place when the catch 27 is moved completely out of line with the latch 28 on the wringer head, the partial or restricting blocking of the movement of the wringer frame relative to the head is sufficient to prevent actuation of the safety release until the latch release bar 24 is moved from the position it occupies when the roll pressure is released.

As the roll pressure is released either instinctively or manually, the toggle links 19, 20 swing upward in a counterclockwise direction about their respective pivots 22 and 23, thereby moving the top bar 12 upward and releasing the pressure between the wringer rolls 9 and 10. The roll pressure is reset by moving the toggle links in a clockwise direction, as viewed in Fig. 1, using the longer outer toggle link 20 as a handle to secure the leverage desirable for resetting the roll pressure. As the toggle links approach the Fig. 1 position, the lower end of the toggle link 20 engages the projection 31 on the latch release bar 24 and moves it to the left, thereby permitting

5

10

15

20

What is claimed as new is:

1. In a wringer, a support, a roll carrying frame pivoted on the support and including releasable and resettable roll pressure sustaining means and a safety release for the roll pressure sustaining means, a part associated with the safety release moveable to one position in the set condition of the safety release and to another position in the released condition of the safety release, means actuated in response to a predetermined amount of pivotal movement of the frame relative to the support for releasing the safety release, resetting means for the roll pressure sustaining means and the safety release, and means adapted to engage said part in said other position but not in said one position for restricting the pivotal movement of the frame to less than the predetermined amount required for releasing the safety release until the roll pressure sustaining means and the safety release for the roll pressure sustaining means are reset.

2. In a wringer, a support, a roll carrying frame pivoted on the support, said frame comprising a bottom frame and a separable top frame connected to the bottom frame at the end remote from the support by toggle links which in set position resist separation of the top frame and when released permit separation of the top frame under roll pressure, a release member movable toward and away from the support extending beneath the bottom frame and moved by the toggle links toward the support as the toggle links are moved to the set position, said release member cooperating with the toggle links to effect release of the toggle links when moved away from the support, means urging the release member away from the support, a latch on the support cooperating with the release member to hold it against movement away from the support, said latch being released by a predetermined amount of pivotal movement of the frame relative to the support, and parts on the release member cooperating with the latch to restrict pivotal movement of the frame relative to the support to less than the predetermined amount required to release said latch as the release member moves away from the support.
